UNITED STATES PATENT OFFICE.

MATTHEW GOULD, OF BELFAST, IRELAND, ASSIGNOR TO CHARLES McCLOSKEY AND HENRY McCLOSKEY, OF BELFAST, IRELAND.

MACHINE FOR DOING OPENWORK-STITCHING.

No. 884,330.

Specification of Letters Patent.

Patented April 7, 1908.

Application filed January 10, 1906. Serial No. 295,409.

To all whom it may concern:

Be it known that I, MATTHEW GOULD, a subject of the King of Great Britain, residing at 64 Christopher street, Belfast, Ireland, 5 mechanic, have invented certain new and useful Machines for Doing Openwork-Stitching, of which the following is a specification.

This invention relates to sewing machines of the class in which the needles are caused 10 to vibrate laterally so as to produce zig-zag or open-work stitching.

The object of my invention is to so make such machines that two or more parallel and adjacent rows of zig-zag stitching can be 15 made on fabrics. In hemstitching and like work punches are arranged in connection with the needles so as to produce openwork stitching.

Under my invention the needles work together and they are simultaneously moved 20 in the same direction, that is, to the one side or other so as to make the double zig-zag stitch. The needles are not moved near to and then away from one another as in the 25 well known spoke stitch machine.

In order that my said invention may be clearly understood I have hereunto appended explanatory drawings whereon:—

Figure 1 is a side elevation of a spoke 30 stitch machine of well known type with my improvements applied thereto. Fig. 2 is a plan of the machine. Fig. 3 is a view of the cam for operating the vibrating quadrant which vibrates the needles. Fig. 4 is a view 35 of the needle blocks with their needles. Fig. 5 is a cross section taken on the line x, x , Fig. 4 and showing the arrangement of the needles and punches. Fig. 6 is a diagram showing the stitching.

40 On the drawings the same reference letters wherever repeated indicate the same parts.

In carrying out my invention, say for producing two rows of hemstitching on handkerchiefs, I arrange on the needle bar a of a 45 Wheeler & Wilson spoke stitch machine, two vibrating blocks b, c , the block b being provided with a needle e and the block c with a needle f . The needle bar has, fitted to it, two punches g, h , the punch g being at the 50 back of the needle e and the punch h at the front of the needle f . The needle block b has a rod i secured to it and this rod, at its upper end, is attached in the usual manner

to a link k which has, at its one end, a guide slot k^1 working on the pin k^2 and, at its other end, is connected adjustably to the usual vibrating quadrant l which is fulcrumed at l^1 . The needle block c has also a rod j secured to it which, at its upper end, is connected in the usual manner to a link m having, at its one end, a guide slot m^1 working on a pin m^2 , and, at its other end, is adjustably connected to a second vibrating quadrant n fulcrumed at n^1 .

Instead of the usual cam for operating the vibrating quadrants, I use a special cam p 65 which is shown at Fig. 3 to an enlarged scale. This cam is made with projections at 1 and 2 and depressions at 3. Both ends of the cam are duplicates. The pin o of the quadrant l and the pin o^1 of the quadrant n 70 work in the groove of the cam.

It will be seen, especially from the enlarged view, Fig. 4, that the needle blocks are arranged close together and so also are the needles and punches. Of course the 75 shuttles or hooks would be correspondingly arranged.

The cam p is rotated in the usual manner by means of gearing from the shaft in the arm and as it rotates the so called quadrants 80 l, n , are caused to vibrate and they communicate their movements to the links k, m , the rods i, j , and the needles e, f . When the pins o, o^1 are in the position shown at Fig. 3, that is, at the points 1 of the cam, they move the 85 quadrants l, n , away from one another to their fullest extent and bring the needles in line with the punches (see full lines, Fig. 4) and when the pins are opposite the points 2 of the cam the same thing occurs but when 90 the pins are at the points 3 of the cam the quadrants are brought near to one another with the result that the needles e, f , are moved to the one side, the needle f being moved away from the punches while the 95 needle e is moved from its position opposite the punch g to a position opposite the punch h . In this manner the needles are moved simultaneously either to the one side, as clearly indicated in dotted lines at Fig. 4, or to a position in line with the punches, as clearly indicated in full lines at Fig. 4. The lateral movement of the needles is to the right hand side of Fig. 1 but of course it may be to the left hand side according to the position of 100 the hem. The feed mechanism is the same

as that employed in the U. S. patent to Joseph Walker #634,970 granted October 17, 1899.

I will now describe the formation of the 5 stitch with reference to the diagram at Fig. 6. When the pins o, o' , are in the position shown at Fig. 3, that is, opposite the parts 1, 1, of the cam, then the needles e, f , are in line with the punches g, h . The cloth is 10 meanwhile being fed forward and at the end of its forward movement the needles enter it at l, l , (Fig. 6). After the needles rise again, the cloth moves backwards and when the backward movement ceases the parts 2, 15 2, of the cam are acting on the pins o, o' , and the needles enter the cloth at 2, 2, (Fig. 6). When the needles rise again, the cloth is again moved forward, and, at the same time, the cam moves round so as to bring the parts 20 3, 3, opposite the pins, o, o' , with the result that the needles are moved laterally and enter the cloth at 3, 3, (Fig. 6). The usual gap in the feed cam for operating the feed carrier now comes into action and allows the 25 carrier to drop with the result that the cloth remains stationary for an interval. When the gap has been passed the cloth recommences its forward movement and, at the same time, the parts 1, 1, of the cam p come 30 into action on the pins o, o' , with the result that the needles are brought back to their original position opposite the punches and at the next descent they enter the cloth 4, 4; thereafter, the stitches are repeated in the 35 same manner as already explained.

It will be seen that there are two parallel lines of punch holes at 1, 1, 2, 2, but there are no punch holes at 3 where the thread passes through the hem of the cloth.

40 The stitches at the back of the cloth are made in the same manner as on an ordinary Wheeler & Wilson spoke stitch machine.

It will be seen that the needles have two movements in the line of the punches and 45 then a single lateral movement to the one side.

The stitching produces a very pretty effect on handkerchiefs and such like.

By "spoke stitch" I mean a stitch such 50 as shown for instance in the patent to Walker above referred to.

By arranging the punches so that one shall be disposed in the rear of one of the needles I am enabled to better produce the 55 zig-zag stitch with minimum movement.

Having now fully described my invention what I claim and desire to secure by Letters Patent is:—

1. A sewing machine having two needles 60 arranged on the needle bar side by side transversely of the direction of feed, a punch arranged in rear of one needle, a punch arranged in advance of the other needle and means for laterally vibrating both needles simultaneously and in the same direction.

2. A sewing machine having two needles movably arranged on the needle bar side by side transversely of the direction of feed, two punches, one arranged in line with each needle, vibrating means for the needles, and a cam for operating said vibrating means so as to give the needles two consecutive movements in order that they may enter the cloth twice in line with their respective punches and then a simultaneous lateral movement 75 in the same direction to enter the cloth at one side of the punches.

3. A sewing machine having two needles arranged on the needle bar side by side transversely of the direction of feed, a punch 80 arranged in rear of one needle, a punch arranged in advance of the other needle and means for imparting to the needles a simultaneous lateral movement in the same direction at every third descent of the needle 85 bar.

4. A sewing machine having two needles arranged side by side on the needle bar, a punch arranged in rear of one needle, a punch arranged in advance of the other needle 90 and a cam for imparting to the needles a simultaneous lateral movement in the same direction at every third descent of the needle bar.

5. A sewing machine having two needles 95 arranged side by side on the needle bar, a punch arranged in advance of the one needle, a punch arranged in rear of the other needle, and means for causing the needles, during the formation of the stitch, to enter the 100 cloth twice in line with their respective punches and then once to move simultaneously in the same direction at the one side of the punches, and means for imparting to the cloth one backward movement followed 105 by two consecutive forward movements.

6. In a sewing machine the combination with the needle bar, of needles movably secured thereto, rods connected with the needles, links connected to the rods, two 110 quadrants, a cam for operating the quadrants so as to impart to the needles a simultaneous lateral movement in the same direction at every third descent of the needle bar and means for rotating the cam.

7. In a sewing machine the combination with the needle bar of needles movably secured thereto, punches, rods connected with the needles, links connected to the rods, two quadrants for actuating the links, a cam 120 for moving the quadrants away from one another so as to bring the needles in line with the punches twice in each revolution and drawing them together so as to throw the needles to one side of the punches once in each revolution, and means for rotating the cam.

8. In a sewing machine the combination with the needle bar of two needles movably secured thereto, a punch arranged in rear of 130

the needles, a punch arranged in advance of the needles, rods connected with the needles, links connected to the rods, two quadrants for actuating the links, a cam of oblong shape and having two corresponding projections at each end and two corresponding depressions at the center for actuating the quadrants and means for operating the cam.

9. In a sewing machine of the character 5 stated, the combination with the needle bar and needles movably secured thereto, quadrants operatively connected with said needles, and means for moving said quadrants in opposite directions, the needles being at the same time moved in the same direction.

10. In a sewing machine of the character 10 stated, the combination with the needle bar and needles movably secured thereto, of quadrants operatively connected with said 20 needles, and a cam operatively connected with both of said quadrants for moving said

quadrants in opposite directions, the needles being at the same time moved in the same direction.

11. In a sewing machine of the character 25 stated, the combination with the needle bar and needles movably secured thereto, quadrants operatively connected with said needles, means operatively connected with both of said quadrants for moving said quadrants 30 in opposite directions, the needles being at the same time moved in the same direction, a punch arranged in advance of one needle, and a punch arranged to the rear of the other needle. 35

In testimony whereof I affix my signature in presence of two witnesses.

MATTHEW GOULD.
